(57) **CLAIM**

The ornamental design for an emergency device, as shown
and described.

DESCRIPTION

FIG. 1 is a perspective view of an emergency device of our
new design;

FIG. 2 is a front view thereof;

FIG. 3 is a rear view thereof;

FIG. 4 is a top view thereof;

FIG. 5 is a bottom view thereof;

FIG. 6 is a left end view thereof;

FIG. 7 is a right end view thereof;

FIG. 8 is a right end perspective view thereof; and,

FIG. 9 is a left end perspective view thereof, with the
movable ring shown in an alternate position thereof.

The broken lines depict portions of the device that are envi-
ronment and not part of the claimed design.
